W. A. HINES

DIRECTION SIGNAL

Filed June 8, 1923

Patented Apr. 29, 1924.

1,491,859

UNITED STATES PATENT OFFICE.

WILLIAM A. HINES, OF EL RENO, OKLAHOMA.

DIRECTION SIGNAL.

Application filed June 8, 1923. Serial No. 644,212.

To all whom it may concern:

Be it known that I, WILLIAM A. HINES, citizen of the United States, residing at El Reno, in the county of Canadian and State 5 of Oklahoma, have invented certain new and useful Improvements in Direction Signals, of which the following is a specification.

This invention relates to an improved direction signal for motor vehicles and seeks, 10 among other objects, to provide a simple and efficient device whereby a driver may readily signal an intention to turn.

The invention seeks, as a further object, to provide a device which may be readily 15 employed upon sedans of different makes, or which may be used upon open cars.

And the invention seeks, as a still further object, to provide a signal embodying a signal arm which will normally be invisible to 20 traffic in the rear of the vehicle but which may be readily swung manually to project laterally from the vehicle for signaling such traffic.

Other and incidental objects will appear 25 hereinafter.

In the drawings:

Figure 1 is a perspective view showing my improved signal mounted upon a conventional sedan, the signal arm of the device 30 being illustrated in active position,

Figure 2 is a detail sectional view through the device, the signal arm being swung downwardly to inactive position,

Figure 3 is a sectional view on the line 35 3—3 of Figure 2, looking in the direction of the arrows,

Figure 4 is a detail sectional view on the line 4—4 of Figure 2, looking in the direction of the arrows,

Figure 5 is a detail perspective view showing the inner end of the signal arm and one 40 of the clutch members employed, and

Figure 6 is a fragmentary sectional view 45 similar to Figure 2, showing a slight modification of the invention.

In carrying the invention into effect, I employ a bearing tube 10 which may, as 50 illustrated in the drawings, being inserted through the front panel 11 of a sedan, coupé or the like, at the left hand side thereof, and threaded upon the outer end of the tube is a clutch member 12 provided, as shown in detail in Figure 4, with a plurality of radial notches 13. Extending downwardly from 55 said clutch member is a spring arm 14 preferably integral with the clutch member and

extending through the arm are one or more screws 15 sunk into the panel 11 for locking the arm against swinging movement as well as holding the clutch member 12 against rotation. At its lower end portion, the arm is bent forwardly away from the panel and is provided with a horizontally disposed channel member 16. Gripped in said channel member is a stop cushion 17 of rubber or the like, extending forwardly from said member beyond the lines of the adjacent end of the arm as well as projecting at one end of said member. Slidably and rotatably fitting through the bearing tube 10 is a 60 shaft 18 upon the outer end of which is threaded a disc-shaped clutch member 19 provided at its inner side with alined lugs 20 engageable in the slots 13 of the clutch member 12 while at its outer side, said clutch member is, as shown in detail in Figure 5, provided with a diametric slot 21. Fitting over the outer end of the shaft is a signal arm 22 which preferably is gradually 65 widened toward its outer end. The signal arm is preferably formed of sheet metal and is provided with side flanges 23 and 24 meeting at the smaller end of the arm. Pressed inwardly from the arm at opposite sides of the opening therein which receives the shaft 18, are, as shown in Figure 5, alined ribs 25 engaging in the slot 21 of the clutch member 19, locking the arm and said clutch member to turn in unison, and threaded upon the outer end of the shaft is a nut 26 removably 70 securing the arm in position thereon, it being observed that said clutch member is housed by the meeting end portions of the flanges 23 and 24 at the smaller end of the arm. Formed in the flange 23 to freely accommodate the stop cushion 17 is, as particularly brought out in Figure 2, a notch 27. The front face of the arm is preferably 75 painted to correspond to the color of the vehicle to which the device is applied while upon the rear face of the arm is suitably imposed a hand pointing toward the outer end of the arm and preferably the word Safety is, as suggested in Figure 1, also imposed 80 upon the rear face of the arm. Freely fitting over the inner end of the bearing tube 10 is a washer 28 and threaded upon the tube to seat against said washer is a nut 29 co-operating with the clutch member 12 for securing the bearing tube upon the panel 11. 85 Mounted upon the inner end of the shaft 18 is a cup-shaped knob or handle 30 removably 90

ably secured upon the shaft by a nut 31 and interposed between said knob and the inner end of the bearing tube 10 is a spring 32 tending to shift the shaft inwardly and hold 5 the clutch member 19 engaged with the clutch member 12.

As will now be understood in view of the foregoing, by grasping the knob 30 and pushing forwardly thereon for shifting the shaft 10 18 forwardly to disengage the clutch member 19 from the clutch member 12, the knob may be turned for swinging the signal arm 22 upwardly. When so swung upwardly, the arm may, of course, be readily seen from in 15 the rear of the vehicle. To lower the signal arm, the knob 30 is again pushed forwardly when the signal arm will immediately gravitate downwardly to vertical position lying within the lines of the vehicle body so as to 20 be obscured to traffic at the rear of the vehicle. When the arm thus swings downwardly, the arm will travel in front of the stop cushion 17, as shown in Figure 3, until the flange 24 of the arm strikes the projecting end of the cushion so that the cushion will accordingly function to yieldably limit the arm in its downward swinging movement. Upon reaching the limit of its downward movement, the arm will be drawn rearwardly by the spring 32 functioning to engage 30 the clutch member 19 with the clutch member 12 so that the arm will be brought into binding contact with the forward edge of the cushion and rattling accordingly eliminated. A downwardly inclined position of 35 the arm will indicate an intention to stop or slow down; a horizontal position of the arm, an intention to turn to the left; and an upwardly inclined position of the arm, an intention to turn to the right, while by moving the arm up and down a number of times, as suggested in dotted lines in Figure 1, the driver may readily attract the attention of traffic.

45 In Figure 6 of the drawings, I have illustrated a slight modification of the invention wherein I employ a rotatable operating shaft 33 which is inserted through the front panel 34 of the vehicle body and fitting the 50 forward end of the shaft is a clutch member 35 provided at its upper side with an ear 36 and at its lower side with a depending spring arm 37. Extending through said ear and the arm are screws 38 securing the clutch 55 member upon the panel so that said clutch member will serve to rotatably support the shaft 33, and removably mounted upon the outer end portion of the shaft is a coacting clutch member 39 and signal arm 40 identical with the parts 19 and 22 of the preferred 60 construction and secured in like manner. Mounted upon the lower end of the arm 37 is a stop cushion 41 to cooperate with the arm 40, the stop cushion 41 corresponding

to the stop cushion 17 of the preferred construction. At its inner end, the shaft 33 is formed with a crank 42 carrying a handle 43 and bearing between the crank and a washer 44 resting against the inner face of the panel 34, is a spring 45 normally holding the clutch member 39 engaged with the clutch member 35. Thus, as will be seen, this modified structure may be operated by means of the crank 42 in a manner similar to the preferred embodiment of the invention, the modified structure being, however, more simplified.

Having thus described the invention, what is claimed as new is:

1. A direction signal for motor vehicles including a fixed clutch member having a spring arm depending therefrom, a stop cushion carried by said arm, a rotatable longitudinally movable shaft associated with the clutch member and provided with a signal arm adapted to gravitate downwardly limited by said stop cushion, a coacting clutch member carried by the shaft, and a spring acting to shift the shaft longitudinally and hold said clutch members engaged as well as also hold the signal arm against said stop cushion to prevent rattling when said arm is inactive.

2. A direction signal for motor vehicles including a rotatable longitudinally movable shaft, a fixed clutch member associated therewith, a movable clutch member carried by the shaft and provided with a slot, a signal arm secured upon the shaft and having a rib pressed therefrom to engage in said slot securing the arm to turn with the latter clutch member, and a spring tending to shift the arm longitudinally and hold the latter clutch member in engagement with said first mentioned clutch member.

3. A direction signal for motor vehicles including a rotatable shaft mounted for longitudinal movement, a signal arm swingingly supported by the shaft, stop means for said arm, the arm being movable to inactive position in front of said stop means limited thereby, and yieldable means for shifting the shaft longitudinally and binding the arm against said stop means to prevent rattling.

4. A direction signal for motor vehicles including a rotatable shaft mounted for longitudinal movement, a signal arm swingingly supported thereby, a fixed arm extending in the rear of the plane of movement of the signal arm, a stop cushion carried by said fixed arm, the signal arm being movable in front of said cushion to inactive position, and yieldable means for shifting the shaft longitudinally and binding the signal arm against said cushion to prevent rattling.

In testimony whereof I affix my signature.

WILLIAM A. HINES. [L. S.]
